GLYCOL MONOBORATES

William G. Woods, Anaheim, Calif., assignor to United States Borax & Chemical Corporation, Los Angeles, Calif., a corporation of Nevada
No Drawing. Filed May 7, 1962, Ser. No. 193,013
5 Claims. (Cl. 260—462)

The present invention relates to a new class of glycol monoborate compounds, the quaternary ammonium alkyl glycol monoborate halides, and has further reference to a method for preparing the same.

It is, therefore, the principal object of the present invention to provide as new compositions the quaternary ammonium alkyl glycol monoborate halides.

It is a further object of this invention to provide a method for preparing the quaternary ammonium alkyl glycol monoborate halides.

Other objects of the present invention will appear as the description proceeds.

To the accomplishment of the foregoing and related ends, said invention then comprises the features herein-after fully described and particularly pointed out in the claims, the following description setting forth in detail certain illustrative embodiments of the invention, these being indicative, however, of but a few of the various ways in which the principle of the invention may be employed.

Broadly stated, the present invention comprises the quaternary ammonium alkyl glycol monoborate halides of the formula

where R is an alkylene radical of from 2 to 3 carbon atoms in length and containing a total of from 2 to 20 carbon atoms, R₁ is an alkylene radical of from 2 to 3 carbon atoms in length and containing a total of from 2 to 5 carbon atoms, R₂ and R₃ are alkyl radicals of from 1 to 18 carbon atoms, R₄ is selected from the group consisting of benzyl, allyl, and primary alkyl of from 1 to 18 carbon atoms, and X is selected from the group consisting of bromine, chlorine and iodine.

The quaternary ammonium alkyl glycol monoborate halides of the present invention have a wide variety of industrial applications. They can be used in resins and coating compositions as anti-static agents. They have use as active bactericides and fungicides in soap, detergents and in dry cleaning compositions, and they are effective herbicides when used alone or in combination with other phytotoxic materials. Additionally, the present compounds have utility as bacteriostatic agents which prevent microbiological degradation and sludge formation when added to hydrocarbon fuels such as gasoline, jet engine fuels and diesel fuels.

The method for preparing the quaternary ammonium alkyl glycol monoborate halides can best be illustrated by the following equation:

where R, R₁, R₂, R₃, R₄, and X are as defined in the foregoing broadly stated paragraph. The reaction will

proceed when there is an excess of either reactant present. Such excess, however, tends to interfere with the separation of the desired product from the reaction mass, and for the sake of economy and ease of separation, in the preferred embodiment of the invention, I use equimolar amounts of the reactants.

The preferred method for performing the above reaction is a direct single-step process which involves admixing an aminoalkyl glycol monoborate ester with an applicable organohalide, with or without the presence of a heat transfer medium which is inert to the reactants. The reaction mixture is heated to a temperature of from about 50° C. to about 250° C. and the desired quaternary ammonium alkyl glycol monoborate halide is recovered from the resultant reaction mass.

It will be noted that when the organohalide reactant used in the present invention is a lower alkyl halide of from 1 to 3 carbon atoms, the reactant is a gas at the stated reaction temperatures. Therefore, when employing alkyl halides of from 1 to 3 carbon atoms as reactants, I perform the present process in a closed system, to more adequately utilize the reactant by preventing its escape from the reaction system.

It will also be noted that the present reaction will proceed with or without employing an inert solvent as a heat transfer medium. However, the reaction proceeds more readily and the recovery of a substantially pure product is easier when a solvent or heat transfer medium is present, and in the preferred embodiment of the invention the reaction is carried out in the presence of a solvent which is inert to the reactants. The common hydrocarbon solvents such as benzene, n-heptane, xylene, aliphatic naphtha, toluene, etc., are inert to the present reactants and are typical of the solvents which are applicable in the present process.

Referring to the reactants applicable to the present invention, the first of these are the aminoalkyl glycol monoborate esters having the formula

where R is an alkylene radical of from 2 to 3 carbon atoms in length and containing a total of from 2 to 20 carbon atoms, R₁ is an alkylene radical of from 2 to 3 carbon atoms in length and containing a total of from 2 to 5 carbon atoms, and R₂ and R₃ are alkyl radicals of from 1 to 18 carbon atoms. The aminoalkyl glycol monoborate esters are obtained by reacting boric acid or boron trioxide with an applicable glycol and an applicable aminoalkanol. The following example is given to illustrate a method for producing these compounds.

A

A mixture of 103.2 grams (1.00 mole) of N,N-dimethyl-1-amino-2-propanol, 61.84 grams (1.00 mole) of boric acid, and 90.12 grams (1.00 mole) of 2,3-butanediol was placed in a 2-liter round-bottomed flask containing 400 ml. of benzene. The flask was equipped with a reflux condenser, a Dean-Stark trap and a magnetic stirrer, and was heated under reflux for about 8 to 10 hours at which time the theoretical amount of water, 54 ml., had been removed. The excess benzene was then removed by distillation and 149.4 grams (74.3% yield) of 2-(β-dimethylaminoisopropoxy)-4,5-dimethyl-1,3,2-dioxaborolane was recovered, B.P. 131–132° C. (33–8.5 mm.), $n_D^{24.5}$ = 1.452. Chemical analysis of the product yielded the following data:

Calculated for $\text{C}_9\text{H}_{20}\text{BNO}_3$:

	Percent
B	5.38
N	6.97

Found in product:

	Percent
B	5.69
N	6.98

The following list is illustrative of the aminoalkyl glycol monoborate esters applicable to the present invention:

- 2-(β -diisopropylaminoethoxy) - 1,3,2 - dioxaborolane
 2-(β -dioctadecylaminoethoxy) - 4 - methyl-1,3,2-dioxaborinane
 2-(β -dimethylaminoisopropoxy) - 4,5 - dimethyl-1,3,2-dioxaborolane
 2-(β -di - n - hexylaminoisopropoxy)-4,4,6-trimethyl-1,3,2-dioxaborinane
 2-(γ -diethylaminopropoxy) - 4,5 - dimethyl-1,3,2-dioxaborolane
 2-(γ -diisoamylpropoxy) - 1,3,2 - dioxaborinane
 2-(N,N-dimethyl - β - methyl - γ - aminopropoxy)-5-methyl-5-ethyl-1,3,2-dioxaborinane
 2-(N,N-di-n-octyl - β - methyl- γ -aminopropoxy)-4-methyl-1,3,2-dioxaborolane
 2-(N,N-di-n-propyl - β , β - dimethyl- γ -aminopropoxy)-4,4,6-trimethyl-1,3,2-dioxaborinane
 2-(N,N-diisobutyl - β , β - dimethyl- γ -aminopropoxy)1,3,2-dioxaborolane
 2-(N-methyl-N-n-butyl - β - aminoethoxy)-4-propyl-5-ethyl-1,3,2-dioxaborinane
 2-(N-ethyl-N-octadecyl - β - aminoisopropoxy - 4,4,6-trimethyl-1,3,2-dioxaborinane
 2-(N-isopropyl - N - octyl- γ -aminopropoxy)-4-methyl-1,3,2-dioxaborolane
 2-(N-methyl - N - ethyl- β , β -dimethyl- γ -aminopropoxy)-4-methyl-1,3,2-dioxaborolane

The second group of reactants are the organohalides having the formula XR_4 , where R_4 is either a primary alkyl radical of from 1 to 18 carbon atoms, benzyl or allyl, and X is either bromine, chlorine, or iodine. The following list is illustrative of such compounds:

Methyl iodide	n-Decyl iodide
Methyl bromide	n-Dodecyl bromide
Ethyl chloride	n-Hexadecyl iodide
n-Propyl chloride	n-Octadecyl bromide
n-Butyl bromide	n-Hexyl chloride
n-Amyl chloride	Benzyl chloride
n-Hexyl iodide	Benzyl bromide
n-Heptyl chloride	Allyl chloride
n-Octyl chloride	Allyl iodide

It is to be clearly understood that the foregoing lists are only a partial enumeration of the reactants applicable to the present invention and are in no way intended to limit the invention.

So that the present invention can be more clearly understood, the following examples are given for illustrative purposes:

I

A solution of 43.02 grams (0.20 mole) of 2-(β -dimethylaminoethoxy) - 4,4,6 - trimethyl-1,3,2-dioxaborinane and 25.2 grams (0.20 mole) of benzyl chloride were placed in a 1-liter round-bottomed flask containing 100 ml. of benzene. The reaction mixture was heated under reflux in a nitrogen atmosphere for about 6 hours, and then most of the benzene was removed by distillation at atmospheric pressure. The remainder of the benzene was removed by distillation at reduced pressure to yield the desired product, 2-(β -dimethylbenzylammoniummethoxy) - 4,4,6 - trimethyl-1,3,2-dioxaborinane chloride. Chemical analysis of the product yielded the following data:

Calculated for $C_{17}H_{29}BClNO_3$:

	Percent
B	3.17
Cl	10.38

Found in product:

	Percent
B	3.11
Cl	9.84

5

A solution of 77.16 grams (0.30 mole) of 2-(β -diisopropylaminoisopropoxy) - 4,5 - dimethyl-1,3,2-dioxaborolane and 22.96 grams (0.30 mole) of allyl chloride were placed in a 1-liter round-bottomed flask containing 100 ml. of toluene. The reaction mixture was heated under reflux in a helium atmosphere for about 4.5 hours, and then most of the toluene was removed by distillation at atmospheric pressure. The remainder of the toluene was then removed by distillation at reduced pressure to yield the desired product, 2-(β -diisopropylallylammoniumisopropoxy) - 4,5 - dimethyl-1,3,2-dioxaborolane chloride. Chemical analysis of the product yielded the following data:

Calculated for $C_{16}H_{33}BClNO_3$:

	Percent
B	3.24
Cl	10.63

Found in product:

B	3.18
Cl	10.24

III

A mixture of 51.44 grams (0.20 mole) of 2-(γ -diethylaminopropoxy) - 5 - methyl - 5 - ethyl-1,3,2-dioxaborinane and 28.39 grams (0.20 mole) of methyl iodide were placed in an autoclave under a nitrogen atmosphere. The autoclave was heated at from about 150° C. to about 200° C. for about 4 hours. The reaction mass was allowed to cool to about ambient temperature, and the volatile materials were removed from the autoclave by distillation at reduced pressure to yield the desired product, 2-(γ -diethylmethylammoniumpropoxy) - 5 - methyl - 5 - ethyl-1,3,2-dioxaborinane iodide. Chemical analysis of the product yielded the following data:

Calculated for $C_{14}H_{31}BINO_3$:

	Percent
B	2.71
I	31.80
Found in product:	
B	2.67
I	31.03

IV

A mixture of 40.22 grams (0.20 mole) of 2-(β -diethylaminoethoxy)-4-methyl-1,3,2-dioxaborolane and 49.85 grams (0.20 mole) of n-dodecyl bromide were placed in a 1-liter round-bottomed flask containing 150 ml. of xylene. The reaction mixture was heated under reflux in a nitrogen atmosphere for about 6 hours, and then most of the xylene was removed by distillation at atmospheric pressure. The remainder of the xylene was then removed by distillation at reduced pressure to yield the desired 2-(β -diethyldecylammoniummethoxy)-4-methyl-1,3,2-dioxaborolane bromide. Chemical analysis of the product yielded the following data:

Calculated for $C_{21}H_{45}BBrNO_3$:

	Percent
B	2.40
Br	17.75
Found in product:	
B	2.35
Br	17.11

Other modes of applying the principle of the invention may be employed, change being made as regards the details described, provided the features stated in any of the following claims or the equivalent of such be employed.

I, therefore, particularly point out and distinctly claim as my invention:

1. Quaternary ammonium alkyl glycol monoborate halides of the formula

where R is an alkylene radical of from 2 to 3 carbon atoms in length and containing a total of from 2 to 20 carbon atoms, R₁ is an alkylene radical of from 2 to 3 carbon atoms in length and containing a total of from 2 to 5 carbon atoms, R₂ and R₃ are alkyl of from 1 to 18 carbon atoms, R₄ is selected from the group consisting of benzyl, allyl, and primary alkyl of from 1 to 18 carbon

atoms, and X is a halogen selected from the group consisting of bromine, chlorine and iodine.

2. 2 - (β - dimethylbenzylammoniummethoxy)-4,4,6-trimethyl-1,3,2-dioxaborinane chloride.
- 5 3. 2 - (β - diisopropylallylammoniumisopropoxy)-4,5-dimethyl-1,3,2-dioxaborolane chloride.
4. 2 - (γ - diethylmethylammoniumpropoxy)-5-methyl-5-ethyl-1,3,2-dioxaborinane iodide.
5. 2 - (β - diethyldodecylammoniummethoxy)-4-methyl-1,3,2-dioxaborolane bromide.
